DESIGN FOR A SLIP

Norman Hochbaum, New York, N. Y.

Application January 21, 1948, Serial No. 143,951

Term of patent 3½ years

(Cl. D3—26)

To all whom it may concern:

Be it known that I, Norman Hochbaum, a citizen of the United States of America, residing at city of New York, county of New York, and State of New York, have invented a new, original, and ornamental Design for a Slip, of which the following is a specification, reference being had to the accompanying drawing, forming a part thereof:

Figure 1 is a front elevational view of a slip embodying my new design;

Figure 2 is a rear elevational view thereof; and

Figure 3 is a fragmentary enlarged elevation of the lower portion of the slip.

I claim:

The ornamental design for a slip, as shown.

NORMAN HOCHBAUM.
